RAILWAY SIGNALING SYSTEMS

Howard A. Thompson, Edgewood, Pa., assignor to Westinghouse Air Brake Company, Wilmerding, Pa., a corporation of Pennsylvania

Application February 1, 1952, Serial No. 269,475

3 Claims. (Cl. 246—46)

My invention relates to railway signaling systems, and particularly to an improved form of railway signaling system in which the circuits employed for transmitting information concerning traffic governing conditions in advance of a particular location may also be employed to transmit information in the reverse direction.

In conventional railway signaling systems, a stretch of traffic to be protected is divided into sections or blocks, each of which has associated therewith at the entrance end a signal for governing movements of traffic into the block. Such signals may be governed by a combination of track circuits extending through the block to indicate the traffic conditions within the immediate block in advance of a signal, and may also include a line circuit extending to the signal location in advance which line circuit is arranged to reflect the traffic conditions in the next block in advance of a particular wayside signal. Thus when a train occupies the block immediately in advance of a wayside signal, the shunting of the track circuit or track circuits within the block causes the signal to display its most restrictive aspect, and when the train vacates the block immediately in advance of the signal, the track relays pick up to cause the signal to display a caution aspect. When the train vacates the second section in advance of a signal, the line circuit is energized by energy governed over the track relays of the second block in advance so that a relay at the first wayside signal is picked up, to cause the signal at that location to display a clear or proceed aspect.

It may at times be desirable to transmit information over the line circuits in the opposite direction to the usual direction of traffic, to provide information at the end of a block concerning traffic conditions at the entering end. One such application of an arrangement of this type is employed in approach lighting signals in advance, by having a series relay connected in the line circuit, so that when the track relay of the block section is released the line circuit is interrupted and the series approach relay releases its contact, thereby supplying energy to the lamp of the signal in advance of the approaching train. Another condition in which it is desirable to transmit traffic information from the entering end of the block section to the leaving end of the block section is the condition wherein vehicles which will not shunt the usual track circuits are operated over the stretch of railway track, and it is desirable to provide a system for registering the entry and the exit of these vehicles in any particular block section. In this connection, it is also desirable to transmit supplemental information over the line circuit from the exit end of the block to the entrance end of the block to indicate that such registration has been accomplished.

Accordingly, it is an object of my invention to provide, in a railway signaling system of the type employing line wire control for signals governing the movement of traffic in a particular direction, means for utilizing the line circuit for transmitting additional information in the direction opposite to the direction of traffic movement.

Another object of my invention is to provide a railway

2

signaling system arranged to provide protection for non-shunting vehicles traversing the section of track so equipped which will not interfere with the normal operation of the signal system by trains or other shunting vehicles using the stretch.

Another object of my invention is to provide, in a system of the type described, an arrangement whereby the entrance of a non-shunting vehicle into the block section may be registered by suitable circuit means, and whereby this registry will be indicated at the entrance point of the section.

Another object of my invention is to provide, in a system of the type described, a superimposed supplemental system for the protection of non-shunting vehicles, requiring the minimum of apparatus, and adapted to be used with conventional signal systems.

Still another object of my invention is to provide, in a signaling system of the type described employing a pair of line wires for the control of signal aspects in accordance with conditions in advance of the signals, means for at times recurrently interrupting the energy flowing in the line circuit, registering these interruptions at the energized end of the line circuits, and indicating the reception and registry of the impulses at the relay end of the line circuit.

Other objects of my invention and features of novelty thereof will be apparent from the following description taken in connection with the accompanying drawing.

In practicing my invention, I provide, in a railway signaling system of the type employing a pair of line wires for governing the wayside signals in accordance with conditions in advance of the signal, means for recurrently interrupting the line circuit at the receiving or relay end thereof, and means at the other end of the line circuit for detecting the recurrent interruptions of the line circuit, in accordance with a predetermined sequence or pattern of interruption. The reception of the proper sequence or pattern of interruption causes the energization of the line circuit to be changed in a characteristic manner, and this change in the energization is reflected at the receiving end of the line circuit, to thereby indicate that the control information transmitted from the receiving end of the line circuit has been received properly. In a preferred embodiment of my invention, I provide means, such as a push button connected in series with the line circuit, at the entering end of a block section, for recurrently interrupting the line circuit to thereby actuate a series connected relay at the exit end of the block section. The recurrent operation of the series connected relay at the exit end of the block section causes the operation of a counting chain, which counts and registers the number of impulses transmitted by the opening and closing of the line circuit. If the line circuit is recurrently opened and closed in the proper sequence, as determined by the arrangement of the counting chain, a relay is energized to pole change the energy supplied to the line circuit at the exit end of the block section, and thereby cause the operation of a polarity responsive relay at the entering end of the block section, to indicate that the desired conditions have been obtained.

I shall describe one form of railway signaling system embodying my invention, and shall then point out the novel features thereof in claims.

The accompanying drawing is a diagrammatic view of a stretch of railway track equipped with a railway signaling system constructed in accordance with my invention, and which is arranged so that the apparatus normally functions in the usual manner to govern the operation of train proceeding through the stretch, but may be also employed to afford protection to the operators of vehicles which traverse the stretch and which are incapable of shunting the track circuit to cause the operation of the signaling system in its usual manner.

Referring to the drawing, there is shown a stretch of railway track having track rails 1 and 3 which are divided into the customary block sections by the conventional insulated joint 5. Only one complete block section, 2T, is shown in the drawing, together with portions of adjoining block sections 1T and 3T, it being understood that the apparatus for each of the sections is arranged in a manner similar to that shown for section 2T. Traffic normally moves through the stretch in the direction indicated by the arrow on the drawing, that is, from left to right. At the entrance or left-hand end of each of the block sections, there is located a wayside signal, such as signal 2S, which functions to govern the entrance of traffic into the section in advance of the signal. The signals may be of any of the well-known types, and as here shown are of the conventional color light type, having a green lamp G, a yellow lamp Y, and a red lamp R, which when lighted provide a proceed, caution and stop aspect, respectively. Additionally, at each of the signals there is provided an additional marker or auxiliary lamp designated by the reference character M, for purposes which will be subsequently explained. Each of the sections in the stretch, such as section 2T, is equipped with a conventional direct current neutral track circuit comprising a track battery, such as battery 2TB connected across the rails of the section at the exit end thereof, and a track relay, such as track relay 2TR, connected across the rails at the entrance end of the section. The track relays are shunted by the presence of a train in the section and operate to govern the wayside signals thereby, as will be explained in detail subsequently.

Between signal locations, such as signal 2S and signal 3S, there is provided a pair of line wires, such as the wires designated by the reference characters 11 and 13, which are employed to additionally govern the wayside signal at the entrance end of the section, and, in accordance with my invention, to also provide means for providing protection for non-shunting vehicles which are operated through the stretch.

Energy is supplied to the line circuit at the exit end of the block section, and energizes load devices such as polarity responsive relays 2DR and 2MCR at the entrance end of the stretch, which also corresponds to the receiving end of the line circuit. The energy supplied to the line circuit at the transmitting end of the line, corresponding to the exit end of the stretch, also serves to energize a series relay such as relay 3AER. The relays 2DR and 2MCR are of the biased type, in which the contacts of the relay are picked up when and only when energy is supplied through the winding of the relay in the direction indicated by the arrow thereon. The load device which is normally energized by the energy supplied over the line circuit, such as relay 2DR, functions as a signal control relay, and cooperates with the track relay, such as relay 2TR, to govern the indication of the wayside signal. The other line circuit load device, such as relay 2MCR, is normally supplied with energy which is ineffective to pick up the contacts of the relay, but when the polarity of the line circuit is reversed, the second relay picks up, and is used to indicate, at the receiving end of the line circuit, the conditions at the transmitting end of the circuit. The series approach relay, such as the relay 3AER, is connected in series with the circuit for supplying energy to the line wires, and the circuits are arranged so that relay 3AER is picked up at all times except when the line circuit is interrupted, during which time the relay will release its contacts.

In addition to the apparatus described above, there is located at each signal location, means for detecting and registering recurrent pick up and release of the series relay. This apparatus may be of any of the well-known types for counting and registering impulses, such as well-known electron tube circuits, but as here shown comprises a group of counting chain relays, such as relays 3A1, 3A2, 3A3, and 3A4, which are arranged so that the relays op-

erate in sequence as a result of the recurrent operation of the contacts of series relay 3AER, so that upon reception of the proper number of impulses, the counting chain relays will become picked up to thereby cause the reversal of the polarity on the line circuit to indicate at the receiving end of the line circuit that a predetermined condition has been established at the transmitting end of the line circuit.

Energy for the operation of the various apparatus and the energization of the signal lamps is provided by a suitable source of low voltage direct current, such as the battery LB, having its positive and negative terminals designated by the reference characters B and N, respectively.

In addition to the apparatus described above, which is located at each of the signal locations in the stretch, my invention also provides for the inclusion of apparatus in the line circuit at intermediate points in the stretch for the purpose of registering the entrance of a non-shunting vehicle into the stretch at that point. This apparatus would comprise a series push button such as the normally-closed push button 2PB-A, and an auxiliary indicator relay such as relay 2MCR-A, the push button and the relay winding being connected in series with the line circuit at a predetermined point in the stretch. Relay 2MCR-A may indicate its energized condition by any suitable means, such as the lamp 2MKE-A energized by a battery 2MCB over a front contact a of relay 2MCR-A, when the relay is picked up, as shown in the drawing.

It is believed that the description of the operation of the apparatus embodying my invention will be enhanced by describing the manner of operation of the equipment under various traffic conditions.

In the normal condition of the apparatus as shown in the drawing, with no train occupying the stretch, and with no non-shunting vehicle registered in the stretch, the line circuit extending between the signal locations 3S and 2S is energized by energy supplied from the battery at signal location 3S, by a circuit which may be traced from terminal B, through the winding of series relay 3AER, back contact a of relay 3A4, the line wire 11, the normally closed contact of push button 2PB-A, front contact a of relay 2TR (the track relay 2TR being picked up at this time since the track section 2T is unoccupied), the normally-closed contact of push button 2EPB, the winding of relay 2DR from left to right, the winding of relay 2MCR from left to right, the line wire 13 including in series therewith the winding of relay 2MCR-A, back contact b of relay 3A4, back contact a of relay 3MCR, and front contact a of relay 3TR to terminal N. It will be seen therefore, that at this time, with the apparatus in its normal condition, the energy supplied to the line circuit will cause the contact of the approach relay 3AER to be picked up, and the direction of flow of energy will be such that the contacts of relay 2DR at signal location 2S will be picked up, while the contacts of relay 2MCR and relay 2MCR-A will be released, the flow of current through their windings being in the opposite direction to that required to pick these relays up.

It will now be assumed that a train proceeding through the stretch occupies section 1T in the rear of signal 2S. Accordingly, at this time the line circuit, not shown, extending rearwardly from signal 2S in the manner similar to that extending between signal 2S and signal 3S, will be deenergized by the shunting of the track relay associated with section 1T. Accordingly, the series relay 2AER at signal 2S will become deenergized, and its back contact a will establish a circuit for lighting the green lamp G of signal 2S. This circuit may be traced from terminal B at back contact a of relay 2AER, over back contact b of relay 2MCR, front contact b of relay 2TR, front contact a of relay 2DR, and through the green lamp G of signal 2S to terminal N. Accordingly, the signal 2S will display a clear or proceed aspect for the approaching train.

When the train moves into section 2T, the wheels and axles of the train shunt the track circuit and relay 2TR accordingly releases and remains released as long as any portion of the section is occupied by any portion of the train. When contact *b* of relay 2TR releases, it interrupts the circuit previously traced for supplying energy to the green lamp G of the signal and establishes a circuit, obvious on the drawing, for supplying energy to the red lamp R of the signal. Additionally, when contact *a* of relay 2TR releases the flow of energy in the line circuit previously described is interrupted, so that relays 2DR and 3AER are deenergized and these relays release. When contact *a* of relay 2DR releases, it further interrupts the circuit for supplying energy to the green lamp G of the signal, but at the present time, with contact *b* of relay 2TR released, the release of contact *a* of relay 2DR has no effect upon the signal indication. The release of relay 3AER at signal 3S will cause the lighting circuit for this signal to be established in the manner described above for signal 2S, so that signal 3S will display a proceed aspect for the approaching train. Additionally, when contact *a* of relay 3AER releases a circuit is established for supplying energy over the back contact of relay 3AER to the winding of the first counting chain relay 3A1. Accordingly, relay 3A1 picks up and its front contact *a* closes in a circuit for picking up the second counting chain relay 3A2. However, the pick up circuit for counting chain 3A2 is open at front contact *a* of approach relay 3AER, so that relay 3A2 does not pick up at this time.

When the train in question moves past signal 3S into section 3T, track relay 3TR will release and its front contact *a* will further interrupt the line circuit for controlling the relays 2DR and 2MCR at the entrance end of the section. When the rear of the train vacates section 2T, relay 2TR will again be energized and its contacts will pick up. When contact *a* of relay 2TR picks up, it closes the line circuit at the signal location 2S, but, as previously explained, the circuit remains deenergized due to the interruption thereof by front contact *a* of the track relay 3TR. At this time, should a second train be following, a release of the series relay 2AER at signal 2S will cause the signal to display a yellow or caution indication, since at this time front contact *b* of relay 2TR will be closed, but contact *a* of relay 2DR will be released so that a lighting circuit for the yellow lamp Y of signal 2S will be completed upon the deenergization of the series relay 2AER.

When the train vacates section 3T, track relay 3TR will be energized and its front contact *a* will again be closed, reestablishing the circuit for supplying energy over the line wires to the relays 2DR and 2MCR at signal location 2S. Since relay 3A4 remains released at this time, the polarity of the energy supplied over the line wires to relays at signal 2S is of the polarity to cause the contacts of the relay 2DR to pick up, and the contacts of the relay 2MCR will remain released. Accordingly, the signal lighting circuits for signal 2S are again connected in such manner that deenergization of the series relay 2AER by an approaching train will cause the signal 2S to display a green or clear aspect.

Reestablishment of the energy to the line circuit also causes the contact *a* of relay 3AER to become picked up. When contact *a* of relay 3AER picks up, a circuit is established momentarily for the pick up of relay 3A2 which circuit includes front contact *a* of relay 3AER and front contact *a* of relay 3A1. However, the supply of energy to relay 3A1 is cut off when contact *a* of relay 3AER picks up, so that the contact *a* of relay 3A1 releases, after a short time interval, thereby interrupting the supply of energy to the winding of relay 3A2, which subsequently releases. At this time, relay 3A3 cannot pick up since when relay 3AER picks up its contact *a*, the pick up circuit for relay 3A3, which includes front contact *a* of relay 3A2 and back contact *a* of relay 3AER, is broken by con-

tact *a* of relay 3AER before front contact *a* of relay 3A2 closes, so that relay 3A3 remains released.

The apparatus is now restored to its normal position as shown on the drawing. It will be apparent from the foregoing description that the apparatus normally functions in the usual manner of a two-block three-indication signaling system upon the passage of a train through the stretch equipped with this type of arrangement. The most restrictive indication is controlled by the track relays, to denote occupancy or unoccupancy of the stretch immediately in advance of each wayside signal, while the line circuit described above provides an additional control for displaying a yellow or green aspect in accordance with the occupancy or non-occupancy of the second section ahead of the wayside signal, provided of course, that the first section is unoccupied as determined by the track circuit of that section.

It will now be assumed that the operator of a motor car or other vehicle which is not capable of shunting the track circuit desires to place the vehicle upon the rails at the entrance end of one of the sections and proceed therethrough. To establish the necessary protection for the motor car, it is necessary that its presence within a given stretch be registered and that a distinctive indication is provided to warn the engineers of approaching trains of the fact that a motor car has been registered into the section.

To register a motor car in the section from the entrance end thereof, such as at signal 2S, the motor car operator will operate the push button 2EPB twice in succession, with the intervals between operations relatively short. As will be apparent from the previous discussion of the line circuit, each operation of the push button 2EPB causes the line circuit to become deenergized and results in the release of the relay 3AER at the exit end of the section for such time as the push button 2EPB is depressed.

When the motor car operator depresses the push button 2EPB twice at the entering end of the section 2T, the contact *a* of relay 3AER at the exit end of the section will be released, picked up, released, and then picked up again. Upon the first release of contact *a* of relay 3AER energy is supplied to the winding of the first counting chain relay 3A1, so that this relay picks up. When the contact *a* of relay 3AER picks up for the first time, a circuit is established over front contact *a* of relay 3AER and front contact *a* of relay 3A1 to cause the pick up of the second counting chain relay 3A2. When contact *a* of relay 3AER releases in response to the second operation of push button 2EPB, energy is supplied to the third counting chain relay 3A3 by a circuit including back contact *a* of relay 3AER and front contact *a* of relay 3A3. When the contact *a* of relay 3AER is finally picked up after the push button 2EPB is released the second and last time, a circuit is established including front contact *a* of relay 3AER and front contact *a* of relay 3A3 to pick up the fourth counting chain relay 3A4. When relay 3A4 picks up, a stick circuit is established for the relay, which circuit may be traced from terminal B, over a normally closed push button 3XPB, back contact *b* of relay 3A3, back contact *b* of relay 3MCR, front contact *c* of relay 3A4, and through the winding of relay 3A4 to terminal N. Accordingly, at this time relay 3A4 will have its contact picked up and will remain picked up after the previous counting chain relays have released, as a result of the closure of the stick circuit of the relay. When contacts *a* and *b* of relay 3A4 pick up, the supply of energy to the line circuit is pole changed, so that energy is now supplied to the relays at the entrance end of the section by a circuit which may be traced from terminal B through the winding of series relay 3AER, over front contact *b* of relay 3A4, line wire 13 including in series therewith the winding of relay 2MCR-A, the winding of relay 2MCR, the winding of relay 2DR, all from right to left, over the contact of push button 2EPB,

front contact *a* of track relay 2TR, line wire 11 including in series therewith the contact of the push button 2PB—A, and over front contact *a* of relay 3A4 to terminal N. The flow of current in the circuit at this time is such as to cause the contacts of relays 2MCR and 2MCR—A to pick up, and the contacts of relay 2DR will be released and remain released.

The picking up of relay 2MCR at the entrance end of the section causes an indication lamp 2MKE to be supplied with energy by a circuit including front contact *a* of relay 2MCR, to thereby indicate to the operator of the motor car that the registry of the entrance of the motor car in the section 2T has been properly accomplished. Additionally, when contact *b* of relay 2MCR picks up it establishes a circuit for supplying energy to the marker lamp M of signal 2S, in the event that the series relay 2AER should be released by the approach of a train. Accordingly, if the train is approaching section 1T at this time, the lamp M of signal 2S will be lighted, to thereby provide a distinctive aspect from signal 2S, indicating to the engineman of the approaching train that a motor car has been registered in the section in advance, so that the engineman may govern the operation of his train accordingly.

It will now be apparent that the purpose of the push button 2PB—A and the series relay 2MCR—A connected in the line wires in the middle of the block section is for the purpose of permitting the motor car operator to register the entry of his car in case the car is placed upon the tracks at the middle block section. Additionally, the relay 2MCR—A provides an indication at that point as to whether or not a motor car is registered in the block by controlling the indicator light 2MKE—A. It will be apparent that a plurality of push buttons and indication relays may be connected in series in the line circuit at various places throughout the block section, wherever it may be desired to provide for registration and/or indication of the registration of the motor cars in the block section.

When the motor car reaches the exit end of section 2T, the counting chain relay 3A4 may be released to clear out the registration by either one of two means. First, the operator may push the cancellation button 3XBP, which will break the stick circuit for the relay 3A4, or, second, if the motor car is to progress into section 3T, the operation of the push button for registering the car in section 3T will cause relay 3MCR to pick up, in the manner similar to that described for relay 2MCR, and when relay 3MCR picks up, its back contact *b* will interrupt the stick circuit for relay 3A4. In either case, the release of relay 3A4 causes its contacts *a* and *b* to pole change the energy supplied to the line circuit, with the result that the motor car indication relays 2MCR and 2MCR—A will be released, and relay 2DR will be energized as previously described. Such operation will restore the apparatus to its normal condition as shown in the drawing and described heretofore.

It will be noted that when relay 3MCR is picked up, its front contact *a* inserts a resistance R1 in the circuit for supplying energy to the line circuit and the relays 2DR and 2MCR at the entrance end of the block section. This resistance is proportioned so that the current which flows through the line circuit at this time will be insufficient to pick up relay 2DR but will be sufficient to cause relay 3AER to remain energized. Accordingly, when relay 3MCR is picked up by the registry of a motor car in section 3T, signal 3S will display the distinctive indication consisting of the lighted marker lamp M upon the approach of a train, and additionally, the signal in the rear of the section in which the motor car is registered, in this case signal 2S, cannot display better than a yellow aspect, thus warning the engineman of an approaching train that a restrictive condition exists in advance. However, since the relay 3AER remains energized at this time it is possible for a second motor car operator

5 to register his car in section 2T, by operation of the push button 2EPB, to thereby operate relay 3AER in the manner described above to pick up the counting chain relay and register the motor car in section 2T.

The system also functions to register the entry of a motor car and provide cancellation of this registry when the motor car backs out of the section at the same end where it was originally registered into the section. For example, let it be assumed that a motor car operator has registered in section 2T by operation of push button 2EPB at signal 2S, in the manner described above. It will now be assumed that the motor car operator wishes to reverse his direction of travel and back out of section 2T, removing the car from the rails at signal location 2S. After the car is removed from the rails, the motor car operator depresses the push button 2EPB twice in succession, holding the push button depressed for a relatively long interval during the second operation thereof. When the push button is first depressed, relay 3AER will release and its back contact *a* will establish a pick up circuit for relay 3A1. When relay 3AER picks up at the end of the first operation of the push button 2EPB, the circuit for picking up relay 3A2 is established over front contact *a* of relay 3AER and front contact *a* of relay 3A1. When relay 3AER is released upon the second operation of push button 2EPB, relay 3A3 is picked up over back contact *a* of relay 3AER and front contact *a* of relay 3A2. The previously traced stick circuit for relay 3A4 is interrupted by the opening of back contact *b* of relay 3A3, and since the pickup circuit for relay 3A4 is open at this time due to the release of relay 3AER, the supply of energy is cut off from relay 3A4, and after a short time interval, relay 3A4 releases, restoring the polarity of the line circuit to normal. Since contact *a* of relay 3AER will remain released for a considerable interval at this time, relay 3A2 will release during this interval, thereby opening the circuit for relay 3A3, which in turn releases, so that when relay 3AER is finally picked up upon the second release of the push button, the circuit for picking up relay 3A4 will not be established, since relay 3A3 will be released and its front contact *a* will hold the pick up circuit for relay 3A4 open.

From the foregoing it will be seen that the arrangement of the circuits as shown in the drawing and embodying my invention provides for the operation of non-shunting vehicles through a stretch of track equipped with a signaling system which operates in the conventional manner for trains and motor vehicles which are capable of shunting the track circuits. Such operation is accomplished by providing means for recurrently interrupting a normally energized line circuit at the receiving end thereof in a predetermined sequence, registering the interruptions at the transmitting end thereof, and providing an indication at the receiving end of the line circuit that the registry has been accomplished by changing the characteristics of the energy supplied over the line circuit.

Although I have herein shown and described only one form of railway signaling system embodying my invention, it will be apparent to those skilled in the art that various changes and modifications may be made therein within the scope of the appended claims without departing from the spirit and scope of my invention.

Having thus described my invention, what I claim is:

60 1. In combination, a source of electrical energy, a load device, a pair of conductors for supplying energy from said source to said load device, said load device being connected to said pair of conductors at one end thereof and said source being connected to said conductors at the other end thereof, means connected between said load device and one of said conductors for at times recurrently interrupting the connections of said load device to said source in a predetermined sequence, detecting means connected to said conductors at the end of said conductors at which said source is located and respon-

sive to changes in the interrupted energy supplied from said source to said conductors, relay means governed by said detecting means and rendered effective when and only when said detecting means is recurrently operated in said predetermined sequence, said relay means operative when rendered effective to change the character of the energy supplied from said source to said conductors, and means associated with said load device for indicating the character of the energy supplied over said conductors to said load device.

2. In combination, a source of electrical energy, a load device, a pair of conductors for supplying energy from said source to said load device, means associated with said load device for at times recurrently interrupting the connection of said load device to said conductors in a predetermined sequence, a series relay connected between said source and said conductors and having contacts which are picked up or released according as energy is or is not being supplied to said load device from said source, counting chain relay means governed by said series relay contacts and rendered effective when and only when said series relay contacts are picked up and released in said predetermined sequence, and means governed by said counting chain relay means for changing the characteristics of the energy supplied to said load device from said source when said counting chain relay means is rendered effective.

3. In combination, a section of railway track over which traffic normally moves in a given direction from a designated entrance end of the stretch to the designated exit end of the stretch, a pair of conductors extending from the entrance end of the stretch to the exit end of the stretch, means for normally supplying direct current energy of a given polarity to said conductors at the exit end of said stretch in accordance with traffic conditions in advance of said stretch, a wayside signal located at the entrance end of said stretch, a signal control relay connected to said conductors at the entrance end of said stretch and responsive to energy of said given polarity for governing said wayside signal, a circuit-interrupting contact at the entrance end of the stretch and effective at times for interrupting said line circuit in a predetermined sequence, registry means including a relay counting chain located at the exit end of said stretch and rendered effective when said line circuit is interrupted in said predetermined sequence for reversing the polarity of the energy supplied to said line circuit from said source, and auxiliary relay means associated with said signal control relay for indicating the reversal of the polarity of energy supplied to said line circuit.

4. In combination, a section of railway track over which traffic normally moves in a given direction from a designated entrance end of the stretch to the designated exit end of the stretch, a pair of conductors extending from the entrance end of the stretch to the exit end of the stretch, means for normally supplying direct current energy of a given polarity to said conductors at the exit end of said stretch in accordance with traffic conditions in advance of said stretch, a wayside signal located at the entrance end of said stretch, a signal control relay connected to said conductors at the entrance end of said stretch and responsive to energy of said given polarity for governing said wayside signal, a circuit interrupting contact at the entrance end of the stretch and effective at times for interrupting said line circuit in a predetermined sequence, registry means including a relay counting chain located at the exit end of said stretch and rendered effective when said line circuit is interrupted in said predetermined sequence for reversing the polarity of the energy supplied to said line circuit from said source, auxiliary relay means associated with said signal control relay and responsive to reversal of the polarity of the energy supplied to said line circuit, and circuit means governed by said auxiliary relay means for causing said wayside signal to display a distinctive aspect.

5. A railway signal system comprising a stretch of track divided into sections, a track circuit including a track relay for each section, a pair of line conductors for each section, at least one of which includes in series therewith a front contact of the associated track relay, energy supply means for each section for supplying the pair of conductors for the section next in the rear with energy of a given polarity in accordance with traffic conditions in advance, a signal control relay for each section 10 receiving energy from said conductors and responsive only to energy of said given polarity, a signal for each section governed jointly by said track relay and said signal control relay, circuit controlling means located at each of said signal locations for at times interrupting said line conductors in a predetermined sequence, a series relay at each signal location and connected in series with the line conductors for the section in the rear, a group of counting relays governed by said series relay, said counting relays being rendered operative when and only when said line conductors are interrupted in said sequence, pole-changing means governed by said counting relays and effective when rendered operative to reverse the polarity of the energy supplied to said line conductors, an auxiliary control relay for each section receiving energy 20 from said conductors and responsive only to energy of reverse polarity, and indication means governed by said auxiliary relay.

6. A railway signal system comprising a stretch of track divided into sections, a track circuit including a 30 track relay for each section, a pair of line conductors for each section, at least one of which includes in series therewith a front contact of the associated track relay, energy supply means for each section for supplying the pair of conductors for the section next in the rear with energy of a given polarity in accordance with traffic conditions in advance, a signal control relay for each section receiving energy from said conductors and responsive only to energy of said given polarity, a signal for each section governed jointly by said track relay and said 35 signal control relay, circuit controlling means located at each of said signal locations for at times interrupting said line conductors in a predetermined sequence, a series relay at each signal location and connected in series with the line conductors for the section in the rear, a group of counting relays governed by said series relay, said counting relays being rendered operative when and only when said line conductors are interrupted in said sequence, pole-changing means governed by said counting relays and effective when rendered operative to reverse the 40 polarity of the energy supplied to said line conductors, an auxiliary control relay for each section receiving energy from said conductors and responsive only to energy of reverse polarity, and means governed by said auxiliary relay for causing said signal to display a distinctive aspect.

7. A railway signal system comprising a stretch of track divided into sections, a track circuit including a track relay for each section, a pair of line conductors for each section, at least one of which includes in series therewith a front contact of the associated track relay, a source of direct current energy for each section for supplying energy to the pair of conductors for the adjacent section in the rear, a pole-changing relay having contacts which govern the polarity of the energy supplied to said conductors from said source, polarized relay means receiving energy from said conductors, circuit controlling means for at times interrupting the flow of energy in said conductors, a series relay having a winding connected in series between said source and said contacts of the pole-changing relay, said series relay having contacts which are picked up or released according as energy is or is not flowing through said conductors, a signal for said section, said signal being governed jointly by said track relay and said polarized relay means energized with energy of 50 a given polarity, a chain of counting relays governed by 55

said series relay and arranged so that the counting relays are picked up sequentially when said line conductors are interrupted in said predetermined sequence, a pick-up circuit for said pole-changing relay including contacts of said series relay and the last relay in said counting chain, a stick circuit for said pole-changing relay including a normally closed circuit controller, and indication means including said polarized relay means for indicating the reversal of polarity of the energy supplied to said line conductors.

8. A railway signal system comprising a stretch of track divided into sections, a track circuit including a track relay for each section, a pair of line conductors for each section, at least one of which includes in series therewith a front contact of the associated track relay, a source of direct current energy for each section for supplying energy to the pair of conductors for the adjacent section in the rear, a pole-changing relay having contacts which govern the polarity of the energy supplied to said conductors from said source, polarized relay means receiving energy from said conductors, circuit controlling means for at times interrupting the flow of energy in said conductors, a series relay having a winding connected in series between said source and said contacts of the pole-
